Attns.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,300,571.

Specification of Letters Patent. Patented Apr. 15, 1919.

Application filed September 14, 1917. Serial No. 191,337.

To all whom it may concern:

Be it known that I, FRED S. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to improvements in fasteners, and more particularly, though not exclusively, to fasteners of the stud and socket type adapted for use in the fastening of the flaps of the pockets of cartridge-belts and the like.

It is among the objects of the invention to provide a stud and socket fastener in which the chances of accidental opening are reduced to a minimum, wherein separation of stud and socket may be readily effected, and wherein separation of stud and socket can be effected even when the relative manipulation of stud and socket is imperfectly effected through ignorance or in the excitement of battle.

In the drawings:

30 Figure 1 is a front elevation of a stud and socket constituting a preferred form of one embodiment of my invention;

Fig. 2 is a section, partly in elevation, on the line 2—2 of Fig. 1;

35 Fig. 3 is a section on the line 3—3 of Fig. 2;

Fig. 4 is an elevation showing the rear plate of the socket proper;

40 Fig. 5 is a section on the line 5—5 of Fig. 4.

Referring to the drawings of the preferred form of stud and socket selected for purposes of illustration, I have shown a stud 6 having a neck 7 and head 8 providing 45 a groove for engagement by resilient jaw means herein typified by the jaw 9 and jaw 10 preferably, as shown, formed of a single piece of wire 11 recessed in a front plate 12.

The front plate 12 is preferably provided 50 with a back plate 13, providing an aperture preferably located, as shown, and in line with an aperture 14 through the front plate 12. The front plate 12 is preferably provided with projections 15 passing through 55 openings 16 in the back plate 13 and

clenched to secure the front and back plates rigidly together in the usual manner. The socket as a whole may be secured to the flap 17 of the pocket by prongs 18 passing through and clenched on a clench plate 19 60 in the usual manner. The stud 6 may be secured to the outside of the pocket in any suitable way.

As before stated, it is among the objects of the invention to provide a fastening 65 which, while very secure, can be readily opened even when not manipulated in precisely the correct manner, and to this end I have died in the back plate 13 a cam portion 20 opposite the end of the jaw 10. The 70 socket may be readily separated from the stud by giving a downward and outward pull to the bottom of the flap 17, which causes the jaw 10 to be wedged against the cam 20 on the back plate 13, the cam 20 being formed to cause the jaw 10 to be wedged 75 downwardly away from the stud and thereby to be disengaged from the shoulder 21 of the stud and permitting separation of the stud and socket. When the operation is 80 performed as above described, the separation of the stud and socket requires the exercise of a very slight pull. It is conceivable, however, that in the excitement of battle the 85 soldier might forget this method of operation and endeavor to open the pocket by a direct outward pull or by an outward and upward pull on the lower flap of the pocket in the manner in which the usual commercial fasteners are operated. In such case 90 the preferred form of stud and socket fastener shown in the drawings will open because the shoulder 21 will crowd the jaw 10 against the inclined portion of cam 20, thereby causing said jaw 10 to ride down 95 the cam 20 and to be separated from the shoulder 21. To effect separation in the latter manner requires the exercise of a much stronger pull than is necessary to separate the ordinary commercial fastener, and also a 100 much greater pull than is necessary to separate the fastener shown in the drawings by a downward and outward pull. The fastener is preferably constructed so that the pull required to separate the stud and socket 105 by a direct outward pull or by an outward and upward pull of the lower flap is greater than any pressure likely to be exerted accidentally.

I have thus provided a stud and socket 110

fastener separable by manipulation in two methods, one of said methods preferably requiring the exertion of less force than the other one. The described fastener is very 5 simple in construction, and certain in its operation, and has many advantages where the dual methods of operation are not necessary. For instance, as a fastener for automobile curtains the stud and socket cannot 10 be separated by force exerted above the axis of the stud in any manner whatsoever.

While I have shown and described a preferred embodiment of my invention, it will be understood that changes involving omission, alteration, substitution and reversal of 15 parts, and even changes in the mode of operation, may be made without departing from the scope of my invention, which is best defined by the following claims.

20 Claims:

1. A separable fastener comprising, in combination, a stud having a head, a socket providing a resilient jaw for engagement with one side of said stud, and a cam on said 25 socket for engagement with said jaw to promote disengagement of said jaw from said stud when said jaw is pressed toward said cam by relative movement of said stud and socket.
- 30 2. A separable fastener comprising, in combination, a stud providing a head and a shoulder, a socket providing a jaw for engagement with said shoulder, and means on the casing for moving said jaw outwardly 35 on said shoulder when said jaw is moved toward the back of said socket by relative moving apart of said stud and socket.
3. A stud and socket fastener comprising, in combination, a stud having a head and a 40 neck; a socket having yielding jaw means; and wedge means carried by said socket, to wedge said jaw means out of engagement with the neck of said stud, said wedge means being operated by a pull on a portion of 45 the socket.
4. A stud and socket fastener comprising, in combination, a stud having a head and a neck, a socket providing yielding jaw means, and means carried by the socket effective to wedge said jaw means out of engagement with the neck of the stud. 50
5. A separable fastener comprising, in combination, a stud having a head and a neck, a socket providing a jaw for engagement with said neck, and means on the casing for wedging said jaw out of engagement with said neck on relative tipping movement of said stud and socket. 55

6. A separable fastener comprising, in combination, a stud having a head and a neck, a socket providing a jaw for engagement with said neck, and means on the casing for wedging said jaw out of engagement with said neck on relative tipping movement in one direction only of said stud and 65 socket.

7. A separable fastener comprising, in combination, a stud having a head and a neck, a socket providing a transverse jaw for engagement with said neck, and means on the casing for wedging said transverse jaw out of engagement with said neck on relative tipping movement of said stud and socket. 70

8. A separable fastener comprising, in combination, a stud having a head and a recessed portion, a socket providing a transverse jaw for engagement with said recessed portion, and means permitting disengagement of said jaw from said recessed portion 80 on downward and outward movement of the bottom of said socket relative to said stud, or on outward and upward movement of the bottom of said socket relative to said stud. 75

9. A separable fastener comprising, in combination, a stud having a head and a recessed portion, a socket providing a transverse jaw for engagement with said recessed portion 90 on downward and outward movement of the bottom of said socket relative to said stud, or on outward and upward movement of the bottom of said socket relative to said stud, said stud and socket being more readily 95 separable by said combined downward and outward movement of the bottom of said socket than by said outward and upward movement of the bottom of said socket. 100

10. A separable fastener comprising in combination, a stud providing a recessed portion, a socket providing a jaw for engagement with said recessed portion, and a back plate having a cam portion thereon for moving said jaw out of engagement with 105 said recessed portion.

11. A separable fastener comprising, in combination, a stud 6 having a head 8, a socket having a front plate 12, a back plate 13, and a jaw 10, and a cam portion for engagement with the jaw 10 to impart movement thereto. 110

In testimony whereof, I have signed my name to this specification.

FRED S. CARR.
